Patented June 12, 1956

178,010

BURNER PILOT TORCH OR THE LIKE

William G. Rowell, Quincy, Mass., assignor to Scully Signal Company, Melrose, Mass., a corporation of Massachusetts

Application April 25, 1955, Serial No. 35,665

Term of patent 14 years

(Cl. D31—2)

Fig. 1 is a perspective view of one side of a burner pilot torch or the like, showing my new design; and
Fig. 2 is a similar view taken from the opposite side.

I claim:
The ornamental design for a burner pilot torch or the like, substantially as shown.
